UNITED STATES PATENT OFFICE.

WILLIAM J. BEISEL, OF BROOKLYN, NEW YORK.

NON-REFILLABLE BOTTLE.

1,324,786.

Specification of Letters Patent. Patented Dec. 16, 1919.

Application filed January 10, 1919. Serial No. 270,544.

To all whom it may concern:

Be it known that I, WILLIAM J. BEISEL, a citizen of the United States, and residing at Brooklyn, county of Kings, State of New York, have invented certain new and useful Improvements in Non-Refillable Bottles, of which the following is a specification.

This invention relates to non-refillable bottles of the type disclosed in my prior Patents Nos. 1,079,387; 1,144,286, 1,144,287 and 1,241,811. As fully disclosed in those prior patents I have invented means for preventing a liquid from entering a bottle and have thus produced a bottle which cannot be refilled and the construction by which this is accomplished includes many novel features as set forth in the above cases one of those features including a tapered valve in the neck of the bottle and a weight down within the body of the bottle connected to the valve by a flexible connection.

This invention involves the use of a different form of weight mounted and connected in a different way from what is shown in my prior patents and this change in construction has certain advantages from the standpoint of ease and cost of production. The new form of weight and its connections, however, are such that they coöperate with the other features of my invention to make an absolutely non-refillable bottle. The novel features of the invention will be apparent from the following description taken in connection with the drawing. In the drawings,

Figure 1 is a vertical section through a bottle having my invention applied thereto;

Fig. 2 is a sectional view through a form of weight which may be used;

Fig. 3 is a detail view of a weight having a modified construction; and

Fig. 4 is a section of another modification.

In the drawings I have shown a bottle having a body portion 1, and an integral neck portion 2. Suspended within the neck portion 2 is a thimble or cylinder 3 provided at its upper or outer end with an annular flange 4 which rests upon the ledge 5 in the neck of the bottle and this cylinder is of such size in cross section and preferably tapers down to the lower end so that it is practically out of contact with the wall of the neck throughout its length. It is provided in its side walls with a plurality of openings or liquid passages 6 and has a central opening 7 in its bottom wall. Above the

integral neck section 2 there is an outer neck section 8, which is attached to the section 2 by a collar 9 which engages grooves or depressions in the two sections preferably by a spinning operation.

Within the neck of the bottle above the end of the cylinder 3 there is arranged a member 10 having at its inner end an annular flange 11 interposed between the two neck sections 2 and 8 and this member 10 is provided with an interior tubular tapered valve seat within which is arranged a suitable valve. The valve shown has a hollow tapered body 12 adapted to fit closely within the valve seat and projecting slightly beyond the inner end of the member 10 into the cylinder 3, the outer end of the valve body being closed by cork 13. A packing 14 may be inserted between the flange 11 and top of the neck section 2. The inner end of the valve 12 is provided with a projection 15 having an eye to which is secured one end of a suitable flexible means 16 which may be in the form of a chain, the other end of which is connected to a weight 17.

Within the neck section 8 of the bottle and resting on top of the section 10 there is a cylindrical member 19, a suitable packing 20 being interposed between it and the member 10. Extending across the neck of the bottle above the cylinder 19 two perforated screens or sieves 21, 22, are placed, these sieves being separated by a cylindrical member 23 which is opaque so that it is not possible to see between the two screens through the neck of the bottle. Above the two perforated screens a guard 24 is placed having a disk 25 closing the top so as to prevent access to the mechanism in the neck of the bottle. This guard has openings 26 in the side for the passage of liquid. A packing 27 may be interposed between its top and the shoulder at the end of the neck section 8. The reduced outlet portion 28 of the neck is provided with screw threads and a screw threaded closure 29 fits over it and has on its interior a piece of cork 30 to make the closure liquid tight.

The weight used in the present invention is preferably in the form of a glass ball which is secured in any suitable way to the inner end of the flexible connection 16. As shown in Fig. 2 it may be provided with a hole 31 through which the connection 16 passes and an enlargement on the end of 16 may serve to support the ball and to pre-

vent it from falling off. When the bottle is in normal vertical position, or in any position except in a substantially straight inverted position, the ball by its weight exerts 5 a pull on the connection 16 and holds the valve 12 to its seat. When the bottle is inverted, however, the ball weight falls by gravity into the space left between the tapered end of the thimble or cylinder 3, and 10 the opposite walls of the bottle and the length of the connection 16 is such that when the ball is in that position there will be no pull on the connection 16, and the valve 12 may be open to discharge liquid. I 15 preferably provide the ball 17 with projections composed of such material as cork which prevent the glass ball itself from striking the parts of the bottle and thus avoid the shock where two hard pieces of glass 20 strike each other. The cork may be mounted in or secured to the ball in various ways. Grooves or depressions 32, which expand toward their inner ends may be provided in the ball and pieces of cork 33 may be forced 25 into those depressions with parts projecting therefrom, as shown in Fig. 2. The tapering form of the depression will hold the cork. In Fig. 3, I have shown round balls 30 of cork 34, mounted and secured in semi-spherical depressions in the ball.

It will be understood from the above description that in order to pour liquid from the bottle it is necessary to hold the bottle in vertical position. In the opening of a valve 35 like valve 12 shown in the drawing, a very little additional opening movement will effect a materially greater discharge from the bottle and will thus greatly improve the action of the device in pouring the liquid 40 from it.

As explained in one of my earlier applications above mentioned, the sieves 21 and 22 absolutely prevent any one from working a hair or anything else flexible around the 45 guard and down to the valve. He would be unable to get anything through the small perforations in the sieves, particularly as he can not see between them. The sieves, however, are so arranged as described in my 50 prior application that there may be a free flow of liquid in emptying the bottle.

While I prefer to make all of the main parts of my device of glass, it will be understood that the use of other material comes 55 within my invention.

In Fig. 4 I have shown the glass ball 17 used as the weight with a central opening or passageway through it contracted at the center 35 having the cylindrical portions 36 60 and 37 of considerable size above and below the contracted portion. I place on this

glass ball a thin cork covering made up of two half spheres 38 and 39 which fit the surface closely and are secured in place in any suitable way. They are provided with inwardly extending cylindrical projections 40 and 41 fitting the openings 36 and 37. A suitable flexible connection which may be a silk thread 42 passes through the parts 40 and 41 and is connected at its other end 70 to the valve 12.

Having thus described the invention what is claimed as new and desired to be secured by Letters Patent is:

1. In a non-refillable bottle the combination with the bottle neck of a valve seat therein, a valve adapted to fit said seat and close the liquid passage through said neck, means above said valve to prevent tampering therewith, a perforated thimble fitting 75 said neck tapering inwardly and provided with a central hole at its bottom, a weight consisting of a glass ball having pieces of cork secured thereto and projecting therefrom at intervals within said bottle below 80 said thimble and flexible means passing through the central opening in said thimble and connecting said valve and weight, the length of the connection and the relations of the parts being such that the weight will exert a pull on said connection and hold the valve in closed position except when the bottle is in substantially inverted position.

2. In a non refillable bottle the combination with the bottle neck of a valve seat 95 therein, a valve adapted to fit said seat and close the liquid passage through said neck, a thimble fitting said neck extending inward and provided with a central opening, a glass ball in said bottle, a flexible connection 100 from said valve to said ball passing through the central opening of said thimble, the said glass ball being provided with depressions in its surface at intervals and pieces of cork secured in said depressions and projecting 105 beyond the surface of the ball.

3. In a non-refillable bottle the combination with the bottle neck of a valve seat therein, a valve adapted to fit said seat and close the liquid passage through said neck, 110 a perforated thimble fitting said neck extending inward and provided with a central opening, a glass ball in said bottle, a flexible connection from said valve to said ball passing through the central opening of said thimble, the said glass ball being provided with depressions in its surface at intervals, larger at their bottoms than at the surface of the ball and pieces of cork compressed and held in said depressions.

In testimony whereof I affix my signature.

WILLIAM J. BEISEL.
